O. S. WIBERG

WINDOW FOR LOCOMOTIVE CABS

Filed Nov. 12, 1924

UNITED STATES PATENT OFFICE.

OKE S. WIBERG, OF CHICAGO, ILLINOIS.

WINDOW FOR LOCOMOTIVE CABS.

Application filed November 12, 1924. Serial No. 749,434.

To all whom it may concern:

Be it known that I, OKE S. WIBERG, a citizen of the United States, residing at Chicago, in the county of Cook and State 5 of Illinois, have invented certain new and useful Improvements in Windows for Locomotive Cabs, of which the following is a specification.

This invention relates, generally, to improvements in windows, but particularly to windows for locomotive cabs, and has for its principal object the provision of an adjustable or swingingly mounted sash or frame within a frame, of such construction 10 and arrangement of its parts that glass lights or panes therefor can be easily removed therefrom and readily and quickly inserted therein, as well as, that when a glass light or pane shall have been inserted 15 in the said sash, it will be securely and safely held in place against accidental dislocation.

Another object is to furnish an adjustable or swingingly mounted sash or frame having the above mentioned characteristics, which is especially adapted, but not restricted thereto, for use in connection with a main or window frame located in a door which permits passage from a locomotive 20 cab to a running board at the side of the engine, which main or window frames are each usually equipped with upper and lower lights or panes of glass separated from each other at their adjacent edges, in which space 25 thus afforded, my improved window is located and operates.

A further object of the invention is, to furnish a window of the above mentioned kind, in which clear or unobstructed vision 30 will be afforded the engineer, when the adjustably or swingingly mounted member thereof occupies either a closed or open position.

Still another object is to so construct parts 35 of the adjustably mounted frame that when in its lowered or closed position interference with the removal of the lower pane of the main frame, should the same require it, on account of being broken or otherwise, 40 will be avoided.

Other objects and advantages of the invention will be disclosed in the following description and explanation.

The invention consists in certain peculiarities of the construction, novel arrangement and combination of the various parts 45

thereof as will be hereinafter more fully set forth and specifically claimed.

In the accompanying drawing,—

Fig. 1 is a front face view of a portion of 50 a window embodying my invention showing parts thereof shortened for the convenience of illustration.

Fig. 2 is a vertical sectional view taken on line 2—2 of Fig. 1 looking in the direction indicated by the arrows.

Fig. 3 is a similar view of a part of the main frame of the window illustrating different positions to which the adjustably mounted sash or frame thereof may be positioned, and

Fig. 4 is a greatly enlarged plan sectional view of one side of the window taken on line 4—4 of Fig. 2.

Corresponding numerals of reference refer to like parts throughout the different views of the drawing.

The reference numeral 5 designates a vertically elongated rectangular frame which may be made of wood or other suitable material and may be employed as a door to permit egress from a locomotive cab to a running board on one side of the engine, or it may be used as a stationary window frame in the front of said cab. This frame 5 has fitted in its upper portion a pane of glass 6 which rests at its lower edge on the upper surface of the top or horizontally disposed rail 7 of a rectangular main frame 8 which is closely fitted in the frame 5, and as is clearly shown in Fig. 1 of the drawing, 50 is of a three-sided rectangular form, that is, the lower horizontal rail or member thereof is omitted, but each of the side rails 9 thereof has at its lower end a horizontal extension 10, which extensions lie in the same plane and project towards each other as shown. The pane of glass 6 may be secured in place by means of cleats 11 secured by means of screws 12 to the frame 5 so as to 55 rest on the outer surface of said pane at its side and upper edges.

The top or horizontal rail 7 of the main frame 8 has at its inner portion a downwardly extended flange 13 as is clearly shown in Figs. 2 and 3 of the drawing, and this flange co-operates with the swingingly mounted frame of the device for a purpose to be presently explained. In the lower portion of the frame 5 a glass pane 14 is vertically mounted and secured in position by means of cleats 11 and screws 12 arranged in 100 105 110

the same manner as those in the upper part of the frame 5. The upper edge of the pane 14 is by preference extended slightly above the extensions 10 on the side rails of the 5 main frame 8, as is clearly shown in Figs. 2 and 3 of the drawings.

The adjustably or swingingly mounted frame or sash of the device is designated as a whole by the numeral 15 and as is clearly 10 shown in Fig. 1 is in the form of a three-sided rectangular figure, that is, has its lower horizontal rail omitted. The upper or horizontal rail 16 of the frame or sash 15 is secured by means of pivots 17 to the upright 15 sides of the frame 8 just below the horizontal or top rail 7 of the frame 8 and outwardly of the flange 13 which depends from the rail 7, and said rail 16 is provided with a longitudinal slot or guide-way 18 for the 20 reception of a pane of glass 19 with which the frame or sash 15 is equipped. Each of the side rails 20 of the frame 15 is provided on its inner surface with a groove or channel 21 to receive and detachably hold the 25 side edges of the pane 19, it being understood that the said grooves 21 terminate at their lower ends or the ends thereof opposite the pivots of the frame 15 short of the side rails 20, thus affording closed ends to support the lower edge of the pane 19 of the 30 swinging frame of the device.

Each of the side rails 20 of the frame 15 is provided in its lower portion with a recess 22 the vertical wall of each of which 35 is downwardly and forwardly inclined, see Figs. 2 and 3, and correspond in shape and size with recesses 23 formed in the lower portion of the side rails 9 of the frame 8, see Fig. 3 of the drawings. By this arrangement it is apparent that when the frame 15 is in its lowered position as shown in Fig. 2 of the drawing, the pane of glass 14 can be removed, if required, without interference by the frame 15, by simply removing the 40 cleats 11 which hold said pane in position, as the beveled or inclined portions of the recesses 22 and 23 of the frame 15 and 8 respectively will permit the pane 14 to be moved at its lower portion forwardly a sufficient distance to be withdrawn from the 45 said recess and its frame.

At a suitable point on its rear surface the frame 5 has mounted on one of its upright sides a bracket 24 which has a screw-threaded opening or socket 25 for the reception of a thumb screw 26 which co-operates with a curved slot 27 in an arm 28 pivoted at one of its ends to a lug 29 on one of the side rails 20 of the frame 15, in such a way as to adjustably support said frame in various positions with respect to the main frame 8 and frame 5, and also in such a way as to firmly secure the frame 15 in its lowered or elevated positions. This thumb screw 26 is 50 removed from the bracket 24 when it is de-

sired to remove a pane of glass 19 from the frame 15 as such a screw 26 must be removed from its socket or bracket to permit the frame 15 to be positioned as shown by dotted lines in Fig. 3, when it is evident the 70 slot or guide-way 18 in the top rail of the frame 15 will be positioned below the flange 13, thus enabling the pane of glass 19 to be removed or a new one easily inserted therein.

From the foregoing and by reference to the drawing it will be readily understood and clearly seen that by my improvements a clear vision window will be provided for the engineer, as it is obvious that when the swingingly mounted frame or sash is in its lowered or closed position as shown in Figs. 1 and 2, there being no bottom rail to said frame or sash or any horizontally disposed rail at the upper edge of the pane 14 to obstruct his vision. It is also apparent that when the frame or sash 15 occupies its lowered position, the pane 19 thereof will overlap the upper part of the pane 14 and thus to a large extent prevent the admission of cinders, rain, snow and dust and the like 80 between the adjacent edges of said panes, as they will be directed downwardly. When in its closed position the adjustable frame or sash 15 can be securely held in such position by tightening the thumb screw 26 so as to hold the arm 28 in about the position shown in Fig. 2 of the drawing. It is also apparent that by my improvements the pane of glass 19 carried by the frame or sash 15, should it become broken or covered with 90 frost or ice, can be instantly removed through the guide-way or slot 18 when the parts are placed in the position shown by dotted lines in Fig. 3 and a clean or unbroken glass can be immediately inserted in 95 said frame or sash.

Having thus fully described my invention, what I claim as new and desire to secure by Letters Patent is:

1. The combination in a locomotive cab and window therefor, of a sash mounted at its top in the frame of the window, said sash being open at its bottom and having a top horizontal and slotted rail pivotally mounted in said frame and provided on the inner surface of each of its sides with a groove in communication at one of its ends with said slot, each groove having its lower end closed, a glass pane removably located in said grooves and slot, and stopping means on said frame arranged to prevent the removal of said glass pane until the sash shall have been turned on its pivots to a predetermined point.

2. In a window of the class described, the combination with an upright frame such as that of a door or window having a glass pane in its lower portion, of a bottomless angular frame fixed in the first named frame with its lower portion adjacent the upper

part of said pane and having at its top a horizontally disposed rail provided with a depending part at its rear edge, a sash open at the bottom and having a top horizontal rail and slotted rail pivotally mounted in said fixed frame below the said top or horizontal rail thereof and in front of its said depending part, a glass pane removably located in said slot, said depending part arranged to prevent the removal of said pane until the sash shall have been turned on its pivots to a predetermined point, a slotted supporting arm pivotally secured at one of its ends to said sash, and a screw extended through said slot and detachably engaging a fixed part.

3. The combination with a fixed rectangular frame having at the rear part of its top rail a depending portion, of a rectangular sash open at its bottom and having a top horizontal and slotted rail pivotally mounted in said fixed frame below the said top or horizontal rail thereof and in front of its said depending part and provided on the inner surface of each of its sides with a groove in communication at one of its ends with said slot, each groove having its lower end closed, a glass pane removably located in said groove and slot, said depending part arranged to prevent the removal of said pane until the sash shall have been turned on its pivots to a predetermined point.

OKE S. WIBERG.
